UNITED STATES PATENT OFFICE

170,777

COMBINED CABINET AND HANGING SHELF UNIT

Harry R. Trout and Frederick M. Hill, Pittsburgh,
Pa., assignors to American Radiator & Standard
Sanitary Corporation, Pittsburgh, Pa., a
corporation of Delaware

Application January 6, 1953, Serial No. 23,031

Term of patent 14 years

(Cl. D33—19)

To all whom it may concern:

Be it known that we, Harry R. Trout and Frederick M. Hill, citizens of the United States, residing at Pittsburgh, State of Pennsylvania, have invented a new, original, and ornamental Design for a Combined Cabinet and Hanging Shelf Unit, of which the following is a specification, reference being had to the accompanying drawing, forming a part hereof.

The figure is a perspective view showing one side and the front of the combined cabinet and hanging shelf unit, embodying our new design.

We claim:

The ornamental design for a combined cabinet and hanging shelf unit, substantially as shown.

HARRY R. TROUT.
FREDERICK M. HILL.
